Des. 239,506
Patented Apr. 13, 1976

239,506

STORAGE TANK FOR LIQUIDS OR THE LIKE

George M. Myers, 3148 N. 47th Drive,
Phoenix, Ariz. 85013

Filed June 19, 1974, Ser. No. 480,953

Term of patent 14 years

Int. Cl. D9—03

U.S. Cl. D9—175

FIG. 1

FIG. 2

FIG. 3

FIG. 4

FIG. 1 is a perspective view of a storage tank, for liquids or the like showing my new design;

FIG. 2 is a top or plan view thereof;

FIG. 3 is a side view thereof; and

FIG. 4 is an end view thereof.

The bottom of the tank is similar to the top thereof as shown in FIG. 2.

I claim:

The ornamental design for a storage tank for liquids or the like, as shown and described.
